Primary Examiner — Mitchell Siegel(57) **CLAIM**

The ornamental design for a fishing rod lure holder, as shown and described.

DESCRIPTION

FIG. 1: is a top, front, left side perspective view of the fishing rod lure holder showing my new design;

FIG. 2: is a top view thereof;

FIG. 3: is a bottom view thereof;

FIG. 4: is a left side view thereof;

FIG. 5: is a right side view thereof;

FIG. 6: is a front view thereof;

FIG. 7: is a rear view thereof;

FIG. 8: is a top view being shown in an open position; and,

FIG. 9: is a front view being shown in an open position.
